UNITED STATES PATENT OFFICE.

VALENTIN WEBER AND JAMES R. HARRISON, OF PRINCEVILLE, ILLINOIS.

AUTOMATIC GRAIN-WEIGHING MACHINE.

SPECIFICATION forming part of Letters Patent No. 369,486, dated September 6, 1887.

Application filed March 26, 1887. Serial No. 232,510. (No model.)

To all whom it may concern:

Be it known that we, VALENTIN WEBER and JAMES R. HARRISON, both of Princeville, in the county of Peoria and State of Illinois, 5 have invented a new and Improved Automatic Weighing-Machine, of which the following is a full, clear, and exact description.

The object of our invention is to provide a new and improved machine for weighing grain 10 automatically as it is received from the thrashing-machine.

The invention consists in the construction and arrangement of various parts and details and combinations of the same, as will be fully 15 described hereinafter, and then pointed out in the claims.

Reference is to be had to the accompanying drawings, forming a part of this specification, in which similar letters of reference indicate 20 corresponding parts in all the figures.

Figure 1 is a side elevation of our improvement in the position for receiving a charge of grain. Fig. 2 is a central sectional elevation of the same. Fig. 3 is a rear elevation of the 25 same. Fig. 4 is an end view of the same, and Fig. 5 is an inverted sectional elevation of the tripping device.

The elevator A, of any approved construction, is connected with the grain-spout of the 30 thrashing-machine, so that the grain is carried upward and is discharged into the downwardly-extending hopper B, provided on each side with a bracket, C, having a knife-edge, on which is fulcrumed the weighing-beam D, supporting on knife-edges at each side the grain-box E, held below the spout B. The other end of the beam D is provided with the usual poise, 35 D', and the downward motion of the beam is limited by the stop D'', secured to the side of 40 the elevator A.

The grain-box E is kept in a vertical position by the links E', pivotally connected with the elevator A and the grain-box E. Said box is open at the top and bottom; but the latter is 45 adapted to be closed by a sliding bottom, F, held in suitable bearings on the grain-box E and connected by links G with the crank-arms H and H', secured on the ends of the transverse shaft H'', held in suitable bearings on 50 the elevator A, passing through the same without interfering with the endless belt and buckets of the elevator.

On the crank-arm H is pivoted the spring tripping-pawl I, adapted to engage with its inner end the ratchet-wheel J, secured to one 55 face of the sprocket-wheel J', turning loosely on the shaft H'', and connected by a sprocket-chain, J'', with the sprocket-wheel J'', secured to the elevator-shaft A', which receives its rotary motion in the usual manner. 60

The outer end of the pawl I is adapted to engage the lug K', formed on the outer end of the lever K, fulcrumed on a pin, K'', secured to the elevator A, and the lever K is pivotally connected at its inner end with the grain-box 65 E. The other crank-arm, H', operates on the lever L, pivoted at its lower end to the elevator A and held in contact with the said crank-arm H' by the spring L'. 70

The upper end of the lever L is pivotally 70 connected by the link N with the gate O, adapted to close the mouth of the hopper B, being secured to the rods O', pivoted on the outer side of said hopper B. To insure an easy movement to the sliding bottom F, and 75 to prevent the grain from clogging in the grain-box E, I provide the latter with a slanting side, E'', which opens upon the pivoted inclined scraper E'', resting with its inner end on top of the said bottom F. 80

The operation is as follows: In the position shown in the drawings the grain-box E is closed at its lower end by the sliding bottom F, the mouth of the hopper B is opened as its gate O is held in the outermost position by 85 the lever L, and the tripping-pawl I is out of contact with the ratchet-wheel J, but is in contact with the lug K' of the lever K. Now, when the elevator A is set in motion in the usual manner, it discharges the grain into the 90 hopper B, which delivers the same into the grain-box E, which thus begins to fill. At the same time the sprocket-wheel J'' is rotated by the elevator-shaft A' and imparts a similar motion by the sprocket-chain J'' to the sprocket-wheel J' and the ratchet-wheel J, which rotate loosely on the shaft H''. As soon as the grain in the grain-box E overbalances the weight to which the scale-beam D is set by its poise D', then the grain-box E moves downward, so that the lever K is caused to swing upward at its outer end, whereby the lug K' 95 disengages the tripping-pawl I, which is forced by its spring into contact with the ratchet- 100

wheel J, so that the pawl is carried with the ratchet-wheel, thereby imparting a rotary motion to the shaft H² and its crank-arms H and H'. The revolving motion of the shaft H² forces 5 the crank-arm H' to move away from the lever L, whereby the latter is moved inward by its spring L', thus causing the gate O, by means of the link N, to swing inward and close the mouth of the hopper B, so that no more grain 10 can enter the grain-box E. At the same time the crank-arms H and H' pull on the sliding bottom F by means of the links G, so that the bottom F slides outward, thereby opening the lower end of the grain-box E, which thus dis- 15 charges its contents. As soon as the grain is discharged from the box E, the weighing-beam D causes the box to rise to its former position until the beam D rests on its stop D². The outer end of the lever K is caused to 20 swing downward by the upward motion of the box E, so that when the tripping-lever I has made one revolution its upper end will again strike the lug K', so that the pawl I turns on its pivot on the crank-arm H, where- 25 by the lower end is disengaged from the ratchet-wheel J, which keeps on turning with the sprocket-wheel J', while the shaft H² and the crank-arms H and H' remain stationary until the tripping-lever is again released, as 30 above described. The crank-arm H' in its last quarter of a revolution pushes the lever L outward to its normal position, (shown in Fig. 3,) whereby the gate O is swung outward from the mouth of the hopper B and the above- 35 described operation is repeated.

It will be seen that the grain-box E is automatically emptied whenever a certain weight (indicated by the beam D) is obtained. Every 40 discharge of the grain-box is counted, so that the total weight of the grain passing through 45 the box E can be easily calculated. A registering device of any approved construction can be connected with the grain-box, so as to register automatically the number of times the grain-box has been emptied.

Having thus fully described our invention, we claim as new and desire to secure by Letters Patent—

1. In an automatic grain-weighing machine, 50 the combination, with a grain-box and a bottom adapted to slide thereon, of crank-arms connected with said bottom, a shaft carrying said crank-arms, a ratchet-wheel rotating loosely on said shaft, and a spring tripping- 55 pawl pivoted on one of said crank-arms and adapted to engage said ratchet-wheel, substantially as shown and described.

2. In an automatic grain-weighing machine, 60 the combination, with a grain-box and a bottom adapted to slide thereon, of crank-arms connected with said bottom, a shaft carrying said crank-arms, a ratchet-wheel rotating loosely on said shaft, a spring tripping-pawl pivoted on one of the arms and adapted to en- 65 gage said ratchet-wheel, and a lever pivotally connected with said grain-box and adapted to

engage said tripping-pawl, substantially as shown and described.

3. In an automatic weighing-machine, a grain-box, a bottom sliding thereon, and a 70 weighing-beam supporting said grain-box, in combination with crank-arms connected with said sliding bottom, a shaft carrying said crank-arms, a ratchet-wheel rotating loosely on said shaft, and a spring-pawl pivoted on 75 one of said crank-arms and adapted to engage said ratchet-wheel, substantially as shown and described.

4. In an automatic grain-weighing machine, a grain-box, a bottom sliding thereon, and a 80 weighing-beam supporting said grain-box, in combination with crank-arms connected by links with said sliding bottom, a shaft carrying said crank-arms, a ratchet-wheel rotating 85 loosely on said shaft, a spring tripping-pawl pivoted on one of said crank-arms and adapted to engage said ratchet-wheel, and a lever pivotally connected with said grain-box and adapted to engage said tripping-pawl, substantially as shown and described. 90

5. In an automatic weighing-machine, a grain-box having one of its sides inclined and a pivoted inclined scraper upon which said inclined side opens, in combination with a sliding bottom held in said grain-box and on 95 which the lower end of said inclined scraper rests, substantially as shown and described. 95

6. In an automatic weighing-machine, a grain-box, a weighing-beam supporting said grain-box, a bottom adapted to slide on said grain-box, and crank-arms connected with said bottom for operating the same, in combination with a hopper opening into said grain-box, a swinging gate adapted to close the mouth of said hopper, a rod pivotally connected with said gate, and a spring-lever connected with said rod and operated by one of said crank-arms, substantially as shown and described. 100

7. In a grain-weighing machine, an elevator-hopper, a swinging gate adapted to close the mouth of said hopper, a rod connected with said swinging gate, and a spring-pawl for operating said rod, in combination with a grain-box, a weighing-beam supporting said grain-box, links for holding said grain-box in position, a bottom adapted to slide on said grain-box, crank-arms connected by links with said sliding bottom, a shaft carrying said crank arms, a tripping-lever pivoted on one 115 of said crank-arms, a lever pivotally connected with the grain-box and adapted to engage said tripping-pawl, and a ratchet-wheel placed loosely on said crank-arm shaft and receiving a rotary motion from the elevator-shaft, substantially as shown and described. 120
